UNITED STATES PATENT OFFICE

ALBERT E. PAGE AND FRANK R. PAGE, OF BROOKLYN, NEW YORK, ASSIGNEES TO
SCOTT & WILLIAMS, INC., OF NEW YORK, N. Y., A CORPORATION OF MASSACHUSETTS

CIRCULAR KNITTING MACHINE

Application filed September 12, 1929, Serial No. 392,178. Renewed July 7, 1931.

This invention has to do with automatic knitting machines of the revolving needle cylinder type. Its particular concern is with a machine for making a stocking with gussets between narrowed and widened portions of the fabric such as the toe. The embodiment of it that is described and shown here is one of which an automatic machine of the type shown in the Robert W. Scott Patent Number 1,152,850, Sept. 7, 1915, forms the basis, but that is modified and supplemented in certain respects to make it capable of knitting automatically a stocking such as that described and claimed in the patent of John M. Allen, No. 1,754,185, dated April 8, 1930. To illustrate one way of making this stocking automatically, there is given here a description of an arrangement of needles with butts of different lengths, a special set of cams for acting on these butts to raise and lower the needles in relation to the active knitting level, and three series of cams on the usual pattern drum, these series being properly related to govern the action of the said special needle cams, together with a mechanism making it possible to knit a seamless toe pocket on the opposite side of the circle of needles from the heel pocket.

In the accompanying drawings—

Fig. 1 is a plan view of the head of a circular knitting machine showing the arrangement of the needles in groups differentiated by the lengths of their butts, and the needle cams for acting on these butts, that are added in accordance with this invention. The knitting cams are omitted.

Fig. 2 is a view in side elevation from the front of the knitting head shown in Fig. 1.

Fig. 3 is a view in elevation of the mechanism for moving two of the needle cams in and out of their respective active positions, this mechanism being a part of that shown in Figures 1 and 2.

Fig. 4 is a view similar to Fig. 2 and of the same parts but showing the needle cam operating mechanism of Fig. 3 with its parts in a different position from that depicted in Figures 1, 2 and 3.

Fig. 5 is a view of the mechanism shown in Fig. 3 but from the opposite side, the parts

being in the position partially shown in Figure 4,

Fig. 6 is a view in elevation of the knitting head shown in Fig. 1 but from the left side of the machine,

Fig. 7 is a view of the main pattern drum showing in elevation the three series of cam lugs that control the special needle cams, together with the levers which transmit motion from the lugs to the said needle cams, this view being supplementary to Fig. 6,

Fig. 8 is a development of the knitting cams and the special needle cams showing their relative heights and positions,

Figures 9, 10 and 11 are separate developments of the three series of cam lugs on the main pattern drum that control the special needle cams, these views being so related that the levers acted on by the cam lugs, as well as the cam lugs that act simultaneously appear on the sheet vertically in line with one another. The arrows indicate the direction of movement of the cams.

Fig. 12 is an illustration of the foot of a stocking that may be made on the machine described herein,

Fig. 13 is a front view in elevation of the clutch and driving mechanism of a circular knitting machine designed to effect an advance of the cylinder with respect to the time of the pattern chain when the change is made from reciprocatory to rotary knitting at the end of the heel and toe,

Fig. 14 is a view in elevation, from the right, of a part of the driving mechanism shown in Figure 13, certain of the parts being broken away to reveal other parts behind them.

The stocking, mentioned above and shown in Fig. 12, which may be made automatically by the machine described in this specification, is characterized principally by having a gusset on each side of the toe pocket between the narrowed and widened segments. In order to simplify the description here, the heel pocket A is shown as being made on half of the needles and the reinforced part S of the foot likewise extends half way around the tube of fabric. Other formations however may be used, for instance, a reduced heel made in

accordance with the disclosure of the Scott Reissue Patent 16,795 dated Nov. 22, 1927.

The toe pocket has the narrowed segment C on the top of the foot and the widened segment D on the bottom, both being non-tubular and made by a reciprocatory movement of the needle cylinder. The looping line is at the bottom of the foot. The narrowing begins on the top of the foot at the course indicated by the point E and continues forward to the point F. A gusset G is formed between the narrowed segment and the widened segment and at its inner end H each gusset is tapered. The reinforcing is begun at the course indicated by the letter J and continues through the forward part of the narrowed segment and throughout the widened segment D to the loopers rounds L, which are made by round and round knitting.

Three types of needles are used in the illustration of the invention shown here (see Fig. 1). A full half of the needles have short butts and are designated by the reference letter N'. The other half is in five groups, including a small group N² with intermediate length butts at one end of the half circle of short butt needles N' and a like number of the needles having the same intermediate length butts forming the group N³ at the other end of the short butt group N'. The larger groups N⁴ and N⁵ have equal numbers of needles with long butts and are located between the groups N² and N³ on either side of the small central group N⁶ which is made up of needles with butts of the same length as those in the groups N² and N³. Thus the group N⁶ is flanked on both sides by groups whose butts are longer than those of the N⁶ group. An arrangement which is suitable for a machine having 300 needles is that in which there are 150 short butt needles in the group N', 19 in each of the groups N² and N³, 45 in each group of the long butt groups N⁴ and N⁵ and 22 in the mid-group N⁶.

The location of the looping line on the bottom of the foot means that the toe pocket is knit on the opposite side of the fabric tube from the heel pocket. It therefore is knit on a different group of needles. In the present instance, the heel pocket is knit on the needles of the short butt group N' and the toe pocket on the needles of the five groups N²-N⁶ making up the other half. If a reduced heel made according to the above-mentioned Scott patent were desired, the short butt group N' would be sub-divided into groups differentiated by the lengths of their butts but nevertheless all would be of a shorter butt length than the groups of the opposite half of the circle.

In circular knitting machines as they are now built the pattern chain, which is the timing device determining when each operation shall occur, moves at regular intervals, each corresponding to a number of full courses.

This chain times the change from round and round to reciprocating knitting for both the heel and the toe pockets, hence normally the change into the toe comes an exact number of complete revolutions after the heel and the same needles are put out of activity at both times and the same needles knit both pockets. In the present machine it is desired to knit the toe pocket on the set of needles opposite from the group N' that knits the heel, and therefore the cylinder is shifted one-half a revolution with respect to the pattern chain at some point between the heel and the toe. Preferably this shift is an advance of the cylinder over the chain and is done while the machine is running by means of the arrangement shown and claimed in the application of Albert E. Page, Serial No. 246,243, filed Jan. 12, 1928, and described hereinafter with reference in particular to Figures 13 and 14. The result of this advance may be summed up by saying that any action of the machine after the advance will occur when any given needle is one-half revolution ahead of the point at which it would be were it not for the advance. Hence the needle at the diametrically opposite point of the circle from the given needle is the one affected by that action.

The way in which a stocking of the Allen type is knit automatically in accordance with this invention and with the arrangement of needles described above, may be outlined as follows. The heel is knit in the usual way by narrowing and widening during reciprocatory movements of the needle cylinder, the needles of the low butt group N' being active. The advance of the cylinder preferably is made while changing from reciprocatory to round and round knitting at the end of the heel in order to save strain on the machine. It could be made when changing into the toe or during the knitting of the foot. The toe is therefore knit on the needles of the groups N² to N⁶, the group of short butt needles N' being raised to the inactive level at the end of the instep by a cam that engages their butts, the other needles having been put previously at a level at which their butts pass under this raising cam. Narrowing by the pickers begins at once and continues until all of the needles except those of the group N⁶ are inactive. Thereupon the groups N⁴ and N⁵ are restored as groups to the active level by cams under the control of the pattern drum, so that the gusset courses can be knit. The narrowing at the inner end H of the gusset is brought about by the regular narrowing pickers which act on the end needles of these two groups. When the gusset courses are completed, the remaining active needles of the groups N⁴ and N⁵ are raised to the inactive level by pattern controlled means (also to be described herein). Then widening is begun by putting the usual widening

picker into operation, the needles of the groups N^4 and N^5 being brought down first and then the needles of the groups N^2 and N^3 until on the last course all of the needles in 5 that half of the circle are active. Following that, the short butt needles N' are lowered by a cam so that the full circle of needles are in position to knit the loopers rounds.

10 *The needle cams*

The cams which raise and lower the needles, are shown diagrammatically in Figure 8, the arrow indicating the direction in which the needles move during round and round knitting. There are the usual upper center cam 357 and lower center cam 356 below the throatplate 559, and the two side stitch cams 360, 361 below and at either side of the two center cams. The other instruments for raising and lowering the needles are the usual two lifting or narrowing pickers 650 and a widening or lowering picker 680. These are the same as those described in the Scott Patent 1,152,850 and are identified here by the 25 same numbers as in that patent.

In addition there are other cams to act on the needles for the special purposes under concern here. These other cams are moved toward and away from the needle cylinder by 30 lever systems extending to the usual main pattern drum 120 where they are acted on by three sets or paths of cams suitably related to one another and to the other cams on the pattern drum to control these needle cams in 35 timed relation to the other knitting operations.

Of these special needle cams, the lowering cam 24 and the raising cam 25 occupy the 40 position and do the work of the usual switch cam and the latter has a special function relation to the making of the toe gussets G. These two cams (see Figs. 1 to 6 inclusive) are formed on the inner ends of two plungers 801, 803, which slide horizontally in a bracket 45 800 on the bedplate B. The plunger 801 which carries the lowering cam 24 normally is held away from the needle cylinder by a spring 802 tensioned between the cam and the outer end of the bracket 800. The plunger 50 803 which carries the raising cam 25 is urged outwardly in a similar manner by a tension spring 804.

These lowering and raising cams 24, 25 are controlled from a single gravity rod 216. 55 For this purpose there are two sets of levers at the outer side of the bracket 800 which transmit the movements of the gravity rod to the cam plungers. One of the levers for the lowering cam 24 is a bell crank 805 which has 60 one arm 806 extending horizontally and another 807 vertically, the latter being toothed to engage the teeth 808 on the lower end of a lever 809 pivoted on a stud 810 on the bracket 800. This lever 809 has an adjustable contact screw 811 at its upper end in

engagement with the outer end of the plunger 801 of the lowering cam 24. The stud 810 also provides a pivotal mounting for a bell crank lever 812 which has a hooked arm 813 extending upwardly and outwardly with a 70 screw 815 therein adapted to rest against the plunger 803 of the raising cam 25. An extension 814 of the hooked arm 813 underlies a part of the bracket 800 which serves as a stop limiting the downward swing of the 75 hooked arm.

The lower end of the vertical gravity rod 216 is connected to a controlling lever 215 (Fig. 7) pivoted on a fixed stud on the frame of the machine, and engaging the main pattern drum 120 in the path of a series 80 511 of cam lugs subsequently described in detail (Fig. 10). The upper end of the gravity rod 216 carries the usual collar above the bed plate B and from this collar extends a pin 816 which lies between the hooked arm 813 and the arm 806 to operate the raising and lowering cams 24, 25. The movement of the rod 216 caused by the series 85 511 of lugs is such as to lift the pin 816 from its lowest position, in which it holds the lever 806 down far enough to move the lowering cam 24 into contact with the needle butts, up through an intermediate position clear of both arms to a range in which it lifts the hooked arm 813 90 and thereby puts the raising cam 25 into one or another of its active positions.

The gravity rod also controls the widening picker 680. For this purpose the collar on the rod 216 has an arm 218 with a boss 100 817 on its end receiving a headed plunger 818. Spring 819 tends to lift this plunger to the extent permitted by a pin 820 beneath the arm 218. The headed plunger, when raised by vertical movement of the gravity rod, engages and lifts the usual lever 690 which causes the widening picker 680 to be lowered. For reasons which will appear as the description proceeds, it is undesirable to 105 lower the picker—as would otherwise happen—below its upper normal inoperative level when the gravity rod is raised to put the cam 25 in the path of the needle butts. It is desirable however to have the picker lowered to its inoperative level when the 110 gravity rod is at the intermediate level where the pin 816 is clear of both the arms 806 and 812. A special stop is provided, therefore, limiting the height to which the head of the plunger 818 can rise. This stop is a finger 115 821 (Fig. 6) secured to the bracket 400 so that its lower end meets the plunger 818 at the desired maximum level for the lever 690. Further rise of the rod 216 merely causes the stud 817 to ride up on the plunger 717 compressing the spring 819. 120

Another of the special cams is a lowering cam 26 mounted on a bracket 830 on the bedplate B between the bracket 800 just described 130 and the knitting cams beneath the usual

throat plate 559. This cam 26 is adapted to render the group of needles N⁴ active as a group after the narrowing in the toe. The bracket 830 may also and preferably does serve as the base for certain other needle cams such as those shown in the Robert W. Scott Patent 1,282,958 dated October 29, 1918 and the same levers may be used to control these other cams. This invention is not concerned with such cams and therefore they are not shown or described here. The cam 26 itself is the inner end of a flat plate 831 held on the upper surface of the bracket 830 by a clamp plate 832 which however permits the cam plate 831 to move and has a stud pin 833 extending into a hole in the said plate to form a pivot therefor. The extent to which the cam plate may swing toward the needles is determined by an eccentric washer 834 that is held by a screw 835 and lies in the path of a lug 836 on the cam plate. A variation of the limit of swing is brought about by turning the eccentric washer 834.

The movement of the cam 26 toward and away from the needles is brought about by a lever 826 pivoted on the bed plate to swing in a horizontal plane. At its forward end, this lever 826 has an upright lug 837 through which a wire 838, connected to the plate 831, extends. A spring 839, around this wire and fixed at its end near the plate 831, bears at its outer end against the lug 837 urging the latter against a nut 840 on the outer end of the wire, or in other words, tending to move the wire in toward the needles whenever the pivoted lever 826 swings so as to move the lug 837 in that direction. The rear end of the lever 826 has an edge 841 that engages the rear face of the cam 842 on the upper end of a thrust rod 463. The latter rests on the main pattern drum in the path of the series 513 of the cam lugs (Fig. 11). When on the face of the drum, the rod 463 puts the pivoted lever 826 in such a position that the cam 26 is held clear of the needle butts; and when raised by a lug on the main drum, the rod 463 moves the lever 826 to such a position that the cam 26 is in the path of the needles with long butts.

On the opposite side of the cylinder from the cam 26, and therefore beyond the knitting cams in the direction of round and round knitting, are special lowering cams 27 and 28 and a special raising cam 29. The two lowering cams are formed as separate plates and both are secured to the upright portion 850 of an arm 851 that is mounted on a stud 852 in a way that allows the arm to swing horizontally. The two lowering cams are spaced apart to permit passage of needle butts. Cam 28 is employed to lower the group of needles N⁴ to active position when starting the toe gusset G. The raising cam 29 is secured to a similar portion of the arm 853 of a lever 854 having a base 855 pivoted on

the bedplate. To enable all three cams to be operated from one control there is an extension 856, of the lever 854, on the opposite side of the pivot point from the arm 853 and this extension has jaws 857 which straddle a pin 858. This pin depends from a lug 859 on the arm 851 that carries the lowering cams 27, 28 (Fig. 1). An outward arm 860 of this same lever 854 is engaged by a horizontal wire 861 that is joined to a bell crank lever 862 extending to the main pattern drum 120. A spring 863 fixed at its other end to a screw in the bedplate B tensions the arm 860 away from the bell crank lever 862 and the rear of the machine. The bell crank lever 862 is pivoted on the stud 450 above the main pattern drum 120 (Fig. 7). The lower end of this lever 862 rests on the drum 120 in the path of a series 512 of cam lugs which will be described further on (Fig. 9).

The mechanism controlling the special needle cams

As mentioned above, the special needle cams 24 to 29 are moved to and from positions in which they engage the needle butts by means of levers actuated by lugs on the main pattern drum 120. This drum is the usual one and is racked around at irregular intervals by a mechanism not fully shown here but disclosed in the well known Robert W. Scott Patent 1,152,850. Only three series of lugs are represented in the drawings as they alone are concerned directly with the activation of the special needle cams. It will be understood however that the drum 120 has other series of lugs for controlling other parts of the machine and that, in the series shown, there may be other lugs for moving the same levers for other purposes.

In Figures 9, 10 and 11 the three series of lugs are shown with the drum engaging levers, on which they act, in the positions which the latter occupy relative to the lugs at a given moment in the rotation of the drum. To make it possible to see at a glance which lugs in the three series are acting on the respective levers at any instant; Figures 9, 10 and 11 are not made as similar developments, all starting from the same point on the drum, but are made to show the three series of lugs in the relative positions which they would occupy if the three levers 862, 215 and 463 engage the drum along a single line parallel to the drum axis. The levers could be so arranged but it is more convenient to mount them as shown in Figure 7.

The series 511 of cam lugs (Fig. 10) acts on the lever 215 which in turn raises and lowers the gravity rod 216, moving the widening picker 680 and the regular lowering cam 24 and the regular raising cam 25 to and from their working positions. The lugs of this series are of five heights and thus, considering also that the face of the drum is equiva-

lent to a lug in determining a position of the gravity rod, the latter may occupy any one of six positions. More heights of lugs may be employed if it is desired to produce the 5 stocking of the Robert W. Scott Reissue Patent No. 16,795 dated Nov. 22, 1927. When there is no lug engaging the lever 215, the gravity rod is in its lowest position which puts the pin 816 at such a level (Figures 2 and 3) that it swings the arm 806 downwardly, with the result that the arm 809 is turned about the stud 810. This moves the plunger 801 with the lowering cam 24 in toward the needles to a point where the cam can engage 15 the butts of all needles (see Figure 1). The cam 25 and the widening picker are not affected in this lowest position of the rod 216 and they remain respectively retracted and in its highest position.

20 A lug of the lowest height in the series 511 (e. g. 511^c, 511^e) raises the gravity rod to a height at which the pin 816 allows the plunger 801 and the cam 24 to be retracted by the spring 802. This level is not high enough 25 however to lift the hooked arm 813 or to cause the arm 218 with the plunger 818 to lift the lever 690. This then may be termed the neutral position of the pin 816. The next higher (e. g. 511^b, 511^e) lug lifts the rod 216 30 to a level where the lever 690 is lifted by the plunger 818, thus lowering the widening pick to its inoperative position below the level of the butts of the raised or inactive needles. At this level, the pin 816 still does not lift the 35 hooked arm 813. The next three heights of lugs of the series have the same effect insofar as selection of the cam to be active is concerned but they differ in the degree of that effect. They all raise the rod 216 to a level 40 at which the pin 816 tilts the lever 813 to push the plunger 803 with the raising cam 25 toward the needles. One of these high lugs (e. g. 511^f) puts the cam 25 in position to engage only the long butts of the needles in 45 groups N⁴ and N⁶ while another height (511^a) of high lug causes it also to engage the butts of intermediate length (needles N² N³ N⁶). This highest lug (511^a) in this series puts the raising cam 25 in to a point where it 50 can engage the butts of all the needles in the machine.

The lowering cam 26 is controlled by the levers from the series of lugs 513. In this same series it is possible to place the lugs 55 for controlling such other special cams as those shown in the Scott Patent 1,282,958 for use during the knitting of the upper part of a stocking, in particular in connection with the transfer of the welt and the making of 60 start-up and anti-run-back courses. Such cams are mounted in the region of the cam 26 and are controlled by the thrust rod 463 and the pivoted lever 826.

65 The special lowering cams 27, 28 and the special raising cam 29 are moved alternately

into operative position by the series 512 having lugs of two heights which with the drum face determine three positions of the wire 861 and lever 862. When the lever 862 rests on a low lug, the wire 861, as shown in 70 Figure 1, holds the swinging bracket 854 in a mid-position such that the arm 852 with the cam 29 is clear of the needles and the jaws 857 on the opposite arm 856, by their engagement with the depending pin 858, hold 75 the other swinging bracket 851, with the cams 27, 28 away from the needles. When the lever 862 is dropped to the drum face, it moves the wire 861 forward thus swinging the bracket 854 with the result that the arm 853 with the cam 29 is moved toward the 80 needles enabling the cam to act on the needle butts. A high lug of the series 512 coming under the lever 862 has the opposite effect. It draws the wire 861 back from the mid 85 position against the effort of the spring 863 which, it may be noted, exerts no force in the other positions. The swing of the bracket 854 attendant upon this causes the other bracket 851 with the cams 27, 28 to 90 move in toward the needles due to the fact that the jaws 857 carry the pin 858 in with them as the arm 856 moves in that direction.

95 The cylinder advancing mechanism to cause the heel and toe pockets to be knit on opposite sides of the circle of needles is here shown and described embodied in the usual Scott & Williams type of revolving needle cylinder hosiery machine. In this machine the needle cylinder 260 is driven from the 100 main drive shaft 32 by means of the main bevel gear 31. Motion is communicated to the main drive shaft by a clutch collar 33 splined on the main drive shaft and having a tenon 331. The clutch engages the reciprocating mechanism when its tenon dovetails with the left clutch pinion 35, and with the rotary mechanism when it engages the face 105 of the right clutch pinion 38.

110 When the needle cylinder is to make round-and-round knitting, the clutch collar 33 is to the right with its tenon 331 engaged in a notch in the face 37 of the right clutch pinion 38. This right clutch pinion 38 is unitary with a hollow sleeve 39 on which the driving pulley 42 is mounted. If it is desired to revolve the machine at a different rate of speed, the driving belt can be shifted to a pulley 47, which, while it is free to revolve with relation to the above mentioned 120 hollow sleeve, is connected by a train of gears to the right clutch pinion 38. This train of gears comprises a high speed driving pinion 49 revolving with the pulley 47 and a high speed gear 65 meshing with the pinion 49. This high speed gear or plate gear 65 is carried just outside the frame F of the machine on the shaft 55, and on the other end of the shaft, just inside the frame of 125 the machine, is a quadrant driving gear 60 130

meshing with the previously mentioned right clutch pinion 38.

The left clutch pinion 35 which forms part of the means for reciprocating the circle of needles about its axis is operated from the quadrant driving gear 60 by means of a pitman 70 mounted on this gear 60 and connected to the usual quadrant or sector 75 in such a manner that the revolution of the quadrant driving gear 60 gives an oscillatory motion to the quadrant. It will be observed that the speed of the right clutch pinion 38 is always the same relatively to the average speed of the left clutch pinion 35 and, in the machine shown in the drawings, the gears are so made that the right clutch pinion 38 will make four revolutions while the quadrant 75 is completing one cycle of movement, i. e., one complete stroke in each direction. Assuming that the pulley 42 is used to reciprocate the needle cylinder, the power from the pulley is transmitted through the hollow sleeve 39, the right clutch pinion 38, quadrant driving gear 60, pitman 70 and quadrant 75 to the left clutch pinion 35 where the clutch collar 33 transmits the reciprocatory motion to the main drive shaft 32.

The mechanism used for shifting the clutch collar 33 from one clutch pinion to the other will now be described. This comprises a clutch fork 92 gripping the collar by a peripheral groove and slidably mounted on the machine by a fixed rod 93. There is a clutch cam drum 90 located directly underneath the clutch fork 92 and having a grooved cam path on its circumference. The fork is shifted from left to right by means of a stud 89 on the clutch fork lying in the cam path. This cam drum 90 is racked around under the control of the pattern chain 95 by mechanism which will now be described.

Turning in unison with this clutch drum 90 is a main rack wheel 81 having teeth on its circumference at irregular intervals. This main rack wheel and the clutch drum 90 are fixed tightly on the pattern drum shaft 80. Revolving loosely on this shaft 80 is the sprocket wheel 84 carrying the pattern chain 85 and a chain rack wheel 86 fastened to the sprocket wheel 84.

The pattern chain 85 is racked around at regular intervals from the quadrant 75. This racking of the pattern chain and the quadrant is obtained by means of a pawl 87 on the quadrant acting on the pattern chain rack wheel 86. Since the quadrant always moves in definite timed relation to the right clutch pinion 38 and the shaft 55, it follows that the pattern chain is always racked around at the same speed relatively to the driving pulley—whichever pulley is doing the driving. Since the round-and-round movement of the needle cylinder is always obtained from the right clutch pinion 38 and the quadrant is driven from that pinion, the pattern chain is always

racked at the same speed relatively to the round-and-round movement of the needle cylinder. The to-and-fro movements of the needle cylinder, being obtained through the quadrant 75, also bear a fixed timed relation to the racking of the pattern chain, although that relation is not the same as in the case of round-and-round knitting.

When the clutch collar 33 is in its right hand position in engagement with the clutch pinion 38, the needle cylinder 260 and the clutch pinion 38 revolve in unison, the pattern chain being racked forward once every four revolutions of the needle cylinder. For every such four revolutions the left clutch pinion 35 is turned once in each direction, each revolution of this pinion therefore being equal in duration to two complete revolutions of the needle cylinder during round-and-round knitting. In other words the average speed of the left hand pinion 35 during one turn is half the speed of the right hand pinion 38. Therefore relatively to the pattern chain the angular speed of the needle cylinder during round-and-round knitting is twice as great as its average angular speed during each stroke in reciprocatory knitting.

In the example of the invention shown in the drawings the shifting from round-and-round to reciprocating knitting is unchanged as far as concerns the clutch and quadrant. The chain pawl 87 in racking the pattern chain 85 around brings the lugs on the chain under a pawl controller 83 mounted on the fixed rod 93. This pawl controller has a finger 83c underlying the main pawl 82 carried by the quadrant 75, the pawl being adapted to engage the teeth of the main rack wheel 81. This finger 83c is so positioned as to hold the main pawl 82 out of engagement with the main rack wheel 81 except when the pawl controller is tipped by a lug on the pattern chain. By these means the main rack wheel 81 and the clutch drum 90 can be racked forward whenever desired under control of the pawl controller. The chain pawl 87 and the main pawl 82 are ordinarily moving in opposite directions (Fig. 14). The two pawls are mounted on the quadrant in such a relation and the cams on the surface of the clutch drum 90 are so located that the clutch drum ordinarily forces the clutch collar 33 from engagement with the clutch pinion face 37 to the clutch pinion 35, or vice versa, when the quadrant 75 is in the middle of its downward stroke. At this moment the pinions 35 and 38 are revolving in the same direction and at the same speed and the pinion 38 has just brought the tenon 331 into sufficient register with the groove in the face of the pinion 35 to permit the shifting of the clutch to be made easily. Similarly when shifting from reciprocating to rotary knitting the two pinions are both revolving in the same direction when the shift is made.

As a consequence of the arrangement just described, it may be noted that, when the machine is shifting from to-and-fro knitting to round-and-round knitting, the direction 5 of the last stroke of the cylinder transmitted through the quadrant is a forward stroke, that is it is in the same direction as the motion of the needle cylinder during rotary knitting. Since the average circumferential speed of 10 the needle cylinder during reciprocation is half the speed during rotary knitting, and since shifting of the clutch does not affect the speed with which the pattern chain is racked, it follows that if, when changing 15 from reciprocatory to rotary knitting, the clutch is shifted into engagement with the right clutch face 37 at the beginning of the last stroke, rather than at the middle of that stroke as usual, the needle cylinder will be 20 running at the higher speed of rotary knitting for the whole of that last stroke instead of for half of it, hence for a larger proportion of the total number of drive pulley revolutions or quadrant reciprocations permitted by the pattern chain for any given 25 stocking. As above explained, the quadrant is in its middle position when the shift is ordinarily made from reciprocatory or rotary knitting, and therefore if the shift is to 30 be made at the beginning of the last stroke, it must be made when the quadrant is in its uppermost position, i. e., one revolution of the right driving pinion 38 previous to the normal time. As a result the needle cylinder 35 will have gone half a revolution farther than would have been the case if it had been driven by the quadrant during the movement of the latter from its upper to its half-way-down position. This gives the necessary advance 40 of the needle cylinder for the purpose of knitting the toe on the opposite side of the stocking from the heel, and by making the same change in time of shifting the clutch when coming off the toe, the machine will be 45 brought around again to the proper position for making the heel.

In order to carry out this shifting of the clutch sooner than usual when going off the heel and toe, there is a mechanism other than 50 the usual pawl 82, this mechanism being adapted to rack the cam drum 90 and the main racking wheel 81 slightly sooner than the pawl 82 would do it and in a manner which does not disturb the pattern chain in 55 any way. This mechanism involves an auxiliary hook pawl 116 controlled by a cam 119 on the plate gear 65 giving the shaft 80 a short turn sufficient to shift the clutch shifter fork 92 but without completing the rack for 60 the ordinary change from reciprocatory round-and-round knitting or vice versa as the case may be. In order to accomplish this the cams on the surface of the clutch drum 90 which cause the fork to shift over, are advanced slightly on the surface of the drum. 65

The early racking of the main rack wheel 81 is caused by the cam 119 on the side of the gear 65, engaging one arm of a bell crank lever 118 pivoted on the pattern drum shaft 76. The other arm of that bell crank 70 lever carries the hook pawl 116 adapted to engage one of two teeth 117 mounted on the circumference of the belt shifter drum 102. This belt shifter drum is fast on the pattern chain shaft 80. When the cam on the gear 75 65 hits the bell crank lever the auxiliary pawl will give the shaft 80 and the cam drum 90 a short rack whenever the racking of the main rack wheel has brought the cam on the belt shifter drum within reach of the pawl. 80 One of the teeth on the belt shifter drum is for going off the heel and the other for going off the toe. The pawl 116 is held in contact with the surface of the belt shifter drum by a tension spring 116a. 85

Operation

In the round-and-round knitting of the leg above the heel, the special needle cams are held out clear of the butts. At this time the lever 862 controlling the twin lowering cams 27, 28 and the raising cam 29 rests on the long low cam lug 512e, and the lever 215 for the gravity rod 216 that moves the widening picker and the lowering and raising cams 24, 25 rests on the drum face 120, as does the lever 463 controlling the lowering cam 26. 95

To start the heel, the pattern chain acting through the pawl 82, causes the clutch 33 to shift so that the needle cylinder is driven 100 from the quadrant 75 through the pinion 35. At the same rack the pattern drum puts the cam lug 511a beneath the lever 215 causing the raising cam 25 to be moved into the position in which it engages the long and intermediate butts to raise all of the needles in the half circle made up of the groups N² to N⁶. The position of the rod 216 determined by the lug 511a is that in which the plunger 818 holds the lever 690 up, putting the widening picker 680 at its intermediate idle level below the level of the needles just raised. At the end of the same rack, which is relatively long, the lug 511a moves from beneath the lever 215 so that at its completion the said lever rests on the intermediate lug 511b. 105 The position of the widening picker 680 is unchanged by virtue of the plunger 819 and spring 818 but the raising cam 25 is now in retracted position. 110

On succeeding strokes of the needle cylinder, narrowing takes place in the known way by means of the narrowing pickers 650. After this has continued to the desired point, 115 a short rack of the pattern drum moves the low lug 511c beneath the lever 215 dropping the gravity rod 216 to a level such that the plunger 818 allows the lever 690 to drop, raising the widening picker 680 to the level of the inactive needles. A widening of the seg- 120

ment results in the succeeding courses up to the width where narrowing began, thus completing the heel pocket.

At the beginning of the last forward stroke of the needle cylinder on the widened segment, as the quadrant 75 is halted at the upper limit of its swing, the cam lug 119 on the gear 65 strikes the bell crank 118 and the pawl arm 116 of the latter engages the tooth 117 on the drum 102, the said tooth having just previously come within range of the pawl 116 by a rack of the main rack wheel 81. The result is that the clutch shipper drum 90 is turned and the clutch 33 is moved over into engagement with the high speed pinion. (Fig. 14.) The needle cylinder therefore is driven at high speed through the whole of the last forward stroke of to and fro knitting instead of through only a part of it as usual. This gives the advance of the needle cylinder with relation to the pattern chain. The latter part of this short rack from the pawl 116 brings the low lug 511^c from beneath the lever 215. The latter therefore drops to the drum surface, putting the rod 216 in its lowest position and the lowering cam 24 in place to engage the butts of the inactive needles and restore them to the active level so that they can knit on the first round and round course of the instep.

The balance of the usual rack of the main drum 120 which, were it not for the advance movement of the cylinder, would have shifted the clutch, occurs soon after the shift of the clutch. It effects the yarn change as usual and it also puts the cam lug 512^b beneath the lever 862 causing the latter to swing and put the duplex lowering cam 27, 28 into active position. Since there are no needles at the inactive level the cam 28 does not act but the cam 27 lowers all of the long butt and intermediate butt needles to the ledge 350, as they come from beneath the stitch cam 360. In the instep this has no function as the needles are raised again to the normal low level by the sloping surface 351 of the cam ring ledge. It is desirable however, to use the rack coming off the heel to put this cam in so that it may be in position when the change into the toe is made. During the making of the instep no changes are made in the positions of the needle cams.

When the pattern chain dictates the shift of the clutch 33 which starts the reciprocating of the needle cylinder for the toe, the shift occurs as usual when the quadrant is half way down on a stroke that corresponds to a forward movement of the cylinder, the last revolution of round-and-round knitting. Inasmuch as the needle cylinder is one-half revolution ahead of the position it would have had were it not for the cylinder advance, the half circle of needles that is in front of the throatplate when the shift is made is that which was inactive at the heel,

i. e., the half circle made up of the long and intermediate butt needles. The problem therefore is to raise the short butt needles N' to the inactive level without raising the others.

On the rack of the pattern drum 120 at the change to reciprocatory knitting for the toe, the high lug 511^d is moved under the lever 215 and causes the raising cam 25 to be inserted far enough to engage the short butts of the needles N'. It is to be noted that the lug 511^d for this purpose is higher than the lug 511^a which inserted the cam 25 at the heel but did not put it in far enough to catch the short butts. The cam 25 does not raise the needles in the groups N² to N⁶ for the reason that before reaching this cam these needles were lowered by the cam 27 and they therefore pass up the slope 351 beneath the cam 25. The short butt needles N' are not lowered by the cam 27 and meet the cam 25 at the level of the peak 352.

At the end of the same rack, the raising cam 25 is withdrawn by reason of the lug 511^d moving beyond the lever 215. The lowering cam 27 is also withdrawn, and with it, of course, the cam 28, since the same rack moves the lug 512^b beyond the lever 862, leaving 512^c under the lever.

Thereafter as the to-and-fro knitting continues, the pickers 650 narrow the segment being formed by taking a needle from alternate ends of the active groups N² to N⁶ on each stroke, in the known way. This continues until only the group N⁶ remains.

It is now time to knit the gusset G and the pattern drum is racked on the first forward stroke after completion of the narrowed segment. This brings into action cams 26 and 28 which render groups N⁵ and N⁴ active again. The first part of the pattern drum rack puts the lug 513^a beneath the lever thrust rod 463 and moves the lowering cam 26 into position to engage the long butt needles. The timing is such that this cam goes in opposite the active group N⁶ after the group N⁴ has passed and in time to lower group N⁵ to the first course of the gusset G on one side of the toe.

To bring down the group of needles N⁴ for the gusset on the other side of the toe the high lug 512^d goes under the lever 862 on the same rack and puts the lowering cams 27-28 in part way. This time it is the cam 28 that is active and it lowers the group N⁴ only, as it is not put in far enough to catch the intermediate length of butts of groups N² and N⁶. The end of the same rack moves the lug 512^d from under the lever 862 so that the cams 27-28 are withdrawn and also moves the lug 513^a from under the rod 463 putting the cam 26 out of active position. On the return stroke when the group N⁵ commences knitting, the group N⁴ knits giving the first gusset course on the other side of the toe.

The reason for lowering the two groups N⁴ and N⁶ separately and on opposite sides of the knitting cams is that if the group N⁴ were lowered on the forward stroke before they went through the knitting cams, the loops on these needles would be cast off and no new loops would be taken since the yarn would be behind them, being attached at the end 5 needle of the previously active group N⁶ which just knit on a backward stroke.

On the succeeding strokes, with the groups N⁴ N⁵ and N⁶ knitting, narrowing takes place at the ends of the N⁴ and N⁶ groups to form the tapered inner end H of the gusset. This 15 narrowing is effected by the pickers 650. After the proper number of gusset courses have been knit, the active needles of the groups N⁴ and N⁶ are raised out of action by cams so that the bottom segment of the toe 20 may be knit as usual. To accomplish this a properly timed rack of the main drum puts the high lug 511^f beneath the lever 215 to put the raising cam 25 in to catch the long butts. For this purpose the lug 511^f is 25 slightly lower than the lug 511^a but still higher than the intermediate lugs 511^b and 511^c. This insertion of the cam 25 occurs on the last forward stroke of the gusset in the gap opposite the needles N⁶ so that it raises 30 the active needles of the group N⁶. The active needles of the group N⁴ knit on this stroke along with the ever active N⁶ group, thus giving a last gusset course on the side that had its initial gusset course knit second. 35 The active needles of the group N⁴ are raised by the cam 29 that is inserted on the same rack to catch these long butt needles by reason of the fact that on this rack the lug 512^a goes from under the lever 862 dropping the latter to the drum face and thereby 40 swinging the bracket 851 through the intermediary of the bracket 854 and the pin 858 engaged by the jaws 857.

The end of the same rack throws the cam 45 29 out of action as the long cam lug 512^a is brought beneath the lever 862, and also brings the low lug 511^c under the lever 215 so that the widening picker 680 is made operative and the raising cam is withdrawn. On 50 the next stroke, which is a reverse one, widening begins in the known way, the narrowing pickers 650 lifting one needle for every two brought down by the widening picker 680. 55 The reciprocatory knitting then continues making the bottom toe segment in the usual way, linking it to the gussets and, at the end, to the first part of the narrowed segment beyond the gussets. When the widening is 60 completed the lowering cam 24 is inserted as the lug 511^c is moved from under the lever 215 by a rack of the drum. The lever then rests on the drum face. The cam 24 lowers all of the inactive needles, that is to say the 65 low butt needles N', so that the looping

courses L can be made on the full circle of needles.

In changing to rotary knitting for these looping courses, the second advance of the cylinder is made in order to restore it to its 70 normal relation to the knitting cams for making the top of the next stocking.

We claim—

1. An automatic knitting machine comprising a circular series of independent needles, means adapted to cause formation of seamless heel and toe pockets on said needles, in combination with means adapted to cause said pockets to be formed on opposite sides 75 of said series of needles, and means adapted to render active as a group, after the narrowing for one of said pockets, needles which were put out of action during said narrowing.

2. An automatic circular knitting machine comprising a circular series of independent needles, said series having a group of needles, means adapted to cause formation of seamless heel and toe pockets on said needles, means adapted to cause said pockets to be formed on opposite sides of said series of needles, arranged between two other groups, the butts of the needles of the two latter groups differing in length from those of the first group, means for reciprocating said 80 series of needles about its axis, and devices for gradually narrowing and widening by acting on the needles of the two said flanking groups, together with pattern controlled means for lowering as a group the inactive 85 needles of said two groups and raising the active needles thereof as a group without moving the other needles.

3. An automatic circular knitting machine comprising a circular series of independent needles, said series having a group of needles arranged between two other groups, the butts of the needles of said two flanking groups differing in length from those of the first group, means for reciprocating said series of needles about its axis, and devices for gradually narrowing and widening by acting on the needles of the two said flanking groups, together with pattern-controlled means for lowering the inactive 105 needles of said two groups and raising the active needles thereof, all as groups without moving said first group, and means adapted to knit seamless heel and toe pockets on opposite sides of the series of needles.

4. An automatic circular knitting machine comprising a circular series of independent needles, said series having a group of needles arranged between two other groups, the butts of the needles of said two flanking groups differing in length from those of the first group, means for reciprocating said series of needles about its axis, and devices for gradually narrowing and widening by acting on the 110 needles of said two flanking groups, together 115

- with means adapted to knit seamless heel and toe pockets on opposite sides of the series of needles, means adapted to render active as a group, after the narrowing of one of said pockets, needles which were put out of action during said narrowing. 5. In an automatic knitting machine having a needle cylinder with a circular series of independent needles arranged in groups differentiated by the lengths of the butts, narrowing and widening devices, a device for timing the operations of the machine, a driving mechanism for rotating the needle cylinder continuously or in reciprocating strokes to form a tubular fabric with pockets of narrowed and widened segments, and means for shifting said cylinder from its normal relation to said timing device whereby one pocket is knit on short butt needles and another on longer butt needles, the combination of a cam for raising said longer butt needles to an inactive level during one pocket, a second cam to lift all active needles to an inactive level for the same pocket and a cam for directing the longer butt needles clear of said second raising cam. 10. An automatic circular knitting machine comprising a circular series of independent needles, said series including a group of needles arranged between two other groups whose butts are longer than those of the first mentioned group, means for reciprocating said series of needles about its axis, and devices for narrowing and widening the active series of needles by gradually rendering the needles of said two groups with long butts inactive and active, together with two pattern controlled cams each adapted to lower one of said two groups with long butts only, and a lowering cam adapted to be inserted to take down all needles which may be inactive. 15. An automatic circular knitting machine having a series of independent needles, a longitudinally movable rod, a raising cam and a lowering cam controlled by extreme movements of said rod, in combination with a widening picker and means connecting said rod to said picker, adapted to cause the widening picker to be removed from one level to another by an intermediate movement of said rod and to prevent movement of said widening picker upon extreme upward movement of said rod. 20. A circular knitting machine having a series of independent needles, a longitudinally movable rod, a raising cam and a lowering cam controlled by extreme movements of said rod, in combination with a widening picker, a stop and spring pressed means carried by said rod adapted to move said picker and take against said stop upon an intermediate upward movement of said rod and to permit further upward movement of said rod. 25. A circular knitting machine having a series of independent needles, two lowering cams at different points on the circumference of the needle circle, each adapted to lower needles from the inactive upper level to the active level and another lowering cam adapted to lower needles from the active level to a still lower level, and a raising cam adapted to raise to an upper inactive level needles which were at the active level, to permit needles lowered by the last mentioned lowering cam to pass under it, in combination with lever means carrying said last mentioned lowering cam and one of the two first mentioned lowering cams with a space between said two cams permitting passage of needle butts, and pattern controlled means causing said lever means to be pressed toward the needles until they operate on the butts of some needles but allow others to pass. 30. A circular knitting machine comprising a series of independent needles, said series including a group of needles arranged between two other groups whose butts are longer than those of the first mentioned group, means for reciprocating said series of needles about its axis, and devices for narrowing and widening the active series of needles by gradually rendering the needles of said two groups with long butts inactive and active, together with two pattern-controlled cams each adapted to lower one of said two groups only, the location and time of insertion of said cams being such that the two groups begin to knit on movements in opposite directions. 35. An automatic knitting machine comprising a circular series of independent needles having groups of needles with butts of different lengths, devices for gradually narrowing and widening by acting on the butts of said needles and means operating directly upon the needle butts to raise and lower groups of needles with different butt lengths as units for the purpose of producing gussets between the narrowing and widening, in combination with means adapted to cause the knitting of the seamless heel and toe pockets on opposite sides of the series of needles. 40. A circular knitting machine having a series of independent needles, means adapted to cause formation of a seamless pocket on said needles, said series of needles having groups differentiated from adjacent needles by the length of the butts and spaced from the points corresponding to the corners of the pocket, in combination with means acting directly on the needle butts to raise and lower said differentiated groups of needles as groups for the purpose of producing a gusset in the pocket spaced from the corners of the pocket. 45. In a circular knitting machine, a series of independent needles, the needles on one side of the median line having butts longer than those on the other, and the long butt

side having two groups of needles differentiated from adjacent needles by the length of the butts and spaced from the median line of said circle of needles, in combination with means acting directly on the needle butts to lower and raise said two differentiated groups of needles as units for the purpose of producing a gusset spaced from the corner of the toe pocket between the narrowed and widened segments thereof.

14. In a circular knitting machine, a circle of independent needles having groups with butts of different lengths including two groups whose butts are longer than a group flanked by them, said flanking groups being spaced from the median line of said circle of needles and the butts of all three groups being longer than those on the other side of the median line, in combination with means adapted to cause formation of a seamless pocket on the long butt side of the median line, and other means acting directly on the needle butts to raise and lower said flanking groups for the purpose of producing a gusset between the narrowed and widened segments of the pocket.

15. In a circular knitting machine, a circular series of independent needles, all of the needles on one side of the median line having butts longer than those on the other side, said long butt side including a group arranged between two other groups whose butts are longer than those of the first mentioned group, said flanking groups being spaced from the median line by groups whose butts are shorter than said flanking group butts, means for reciprocating said series of needles about its axis and devices for narrowing and widening on the long butt side of the median line by gradually rendering needles active and inactive, in combination with means adapted to raise and lower said two flanking groups of needles as units during the making of the pocket for the purpose of producing a gusset between the narrowed and widened segments of the pocket.

16. A circular knitting machine having a series of independent needles with butts of different lengths, means to cause formation of a seamless pocket on said needles, said series of needles having groups differentiated from adjacent groups by the length of the butts, in combination with means acting directly on the butts of said differentiated groups of needles only, to raise and lower said groups for the purpose of producing a gusset between the narrowed and widened segments of the pocket.

17. A circular knitting machine having a series of independent needles, means adapted to cause formation of a seamless pocket on said needles, said series of needles having groups differentiated from adjacent needles by the length of the butts and spaced from points corresponding to the corners of the

pocket in combination with means acting directly on the needle butts to return said differentiated groups to the knitting level for the knitting of a gusset in the pocket.

In testimony whereof we have signed our names to this specification.

CERTIFICATE OF CORRECTION.

Patent No. 1,841,205.

Granted January 12, 1932, to

ALBERT E. PAGE ET AL.

It is hereby certified that error appears in the printed specification of the above numbered patent requiring correction as follows: Page 9, line 87, claim 2, beginning with the word "said" strike out all to and including the word "groups" and comma in line 92, and insert instead the words and comma means adapted to cause formation of seamless heel and toe pockets on said needles, means adapted to cause said pockets to be formed on opposite sides of said series of needles, said series having a group of needles arranged between two other groups,; and that the said Letters Patent should be read with this correction therein that the same may conform to the record of the case in the Patent Office.

Signed and sealed this 3rd day of May, A. D. 1932.

(Seal)

M. J. Moore,
Acting Commissioner of Patents.
